ROOF CONSTRUCTION

Salvator S. Calafati, New York, N. Y., assignor
of three-fourths to Salvator S. Calafati, Jr.,
and one-fourth to John M. Cole, both of New
York, N. Y.

Application July 6, 1932, Serial No. 620,998

7 Claims. (Cl. 108—6)

The present invention relates to roof construction.

The present invention contemplates an improved form of roof construction wherein the roofing material is in the form of sheets of insulating material such as wall board. This insulation board provides thermal insulation for the building but it generally is of too porous a nature to function as the only roof covering, and hence the invention also contemplates the application of a suitable impervious coating to the insulating material.

According to the preferred method of laying the roof, the sheets of insulating board of suitable thickness (such as $\frac{3}{8}$ ") are secured to rafters or purlins in courses overlapping in a manner similar to ordinary shingles. The lower edges of the insulation boards are preferably raised up and spaced from the upper surface of the next lower course. After the insulating board has been secured in place hot asphalt, tar (or other impervious material of a nature commonly used for waterproofing) is applied to cover the insulation board and some of this enters the crevices formed between the courses of board. While the coating is still fluid, crushed slate, stone or gravel is sprinkled onto the coating. This provides a more pleasing color than the black of the asphalt or tar, and reduces the amount of radiant heat absorbed by the roof.

Other objects of the present invention relate to an improved roof design which employs metal rafters, and wooden purlins for supporting the insulation board. These parts may be pre-cut to fit and arranged to be readily secured together.

The accompanying drawings show, for purposes of illustration, several embodiments of the present invention, it being understood that the drawings are illustrative of the invention rather than limiting the same.

In the drawings:

Figure 1 is a perspective view of a form of rafters and purlins before the application of the roofing board;

Figure 2 is an elevational view of a metal rafter;

Figure 3 is an enlarged sectional view through the roofing board as applied to the purlins of Figure 1;

Figure 4 is a perspective view of a spacer for use between the layers of roofing board;

Figure 5 is a perspective view of a completed roof;

Figure 6 is a perspective view of a completed roof employing wooden rafters; and

Figures 7 and 8 are views illustrating the se-

curement of a roof rafter to the framing of an adjacent wall.

Figure 1 shows a form of metal roof plate 52 of channel shaped cross-section and designed for use with interchangeable wall forming units having channel shaped frame members such as shown at 26, 21 and 24, as shown in my application Serial No. 620,997, filed July 6, 1932.

Metal rafters 87 rest on the roof plate 52 and are secured in place by angle brackets 86. The rafters are spaced a suitable distance, such as that of four of the interchangeable sections. The one rafter is used alone at the ends of the roof while two rafters may be used back to back as shown at the left. These rafters have upwardly bent lugs 88 formed out of the upper flange of the channel. Purlins 89 are placed above these lugs and secured within by nails 89'.

The purlins 89 are spaced apart a distance corresponding with the desired width of exposure of each course of roof insulating board. Such boards are indicated at 90 in Figures 3 and 5. They are secured in place by nails 91 and spacers 92. The spacers act to hold the lower edge of the upper course away from the surface of the next lower course as will be apparent from Figure 3.

After the insulating boards are secured in place, a coating of hot asphalt, tar, or other suitable waterproofing compound is applied to the same. This coating is preferably applied by a spraying process which forces some of the material up between the layers of roof covering material. The liquid coating is shown at 93. This coating forms a uniform impervious covering for the entire roof and may be used in the valleys as well as along the roof surface.

After the coating is placed and while it is still liquid, crushed slate, stone or other solid material of similar nature is sprayed, sifted or scattered onto the material, as indicated at 93a. These slate or stone particles adhere to the coating and give the roof an improved appearance as well as reduce the heat absorbed by the roof.

The coating material preferably extends down under the lower courses as indicated at 94. It is received above a flashing plate 95 secured to the lower purlin and bent up to embrace the coating and form a drip. A drain or eaves trough 96 is placed below the drip as shown.

The roof shown in Figure 6 is so far as the insulation board, coating and crushed slate, stone, or gravel surfacing, the same as described above. The drawings show such a roof secured to ordinary wooden rafters 97.

Figures 7 and 8 illustrate the securing of a

rafter 87 to the vertical members 32 employed in a gable. Bolt like members 98 have hooked ends 99 to engage the vertical members 32. Nuts 100 clamp the parts tightly together.

5. Insulation board suitable for the purposes of the present invention may be manufactured from the fibres of wood, sugar cane, and the like. Board of this nature is commonly employed in building constructions for purposes of insulation and as a base for plaster.

10. It is obvious that the invention may be embodied in many forms and constructions, and I wish it to be understood that the particular forms shown are but a few of the many forms. Various 15 modifications and changes being possible, I do not otherwise limit myself in any way with respect thereto.

What is claimed is:

20. 1. The method of building roofs which consists in securing pieces of insulating board to a suitable support and in overlapping, shingle-like relation, the lower edges of the insulating board being spaced away from the upper surface of the next lower piece of insulation board, applying a coating of impervious material to the exposed portions of the insulation board, and forcing some of said coating material into said space.

25. 2. The method of building roofs which consists in securing a lower course of roof surfacing material to a roof support, securing a second course of similar material to the support so that a substantial portion of the lower course is exposed, and interposing a spacing member so that the lower edge of said second course is spaced above the upper surface of the first course, and applying hot impervious material to provide an impervious coating over the exposed surfaces and filling said spaces.

30. 3. The method of building roofs, which consists in securing a lower course of insulating board to a roof support and a spacing member substantially midway of the upper surface of the course, securing a second course of insulating board with its lower edge resting on the spacing member so

as to be spaced above the surface of the first course, and applying a hot coating of impervious material over the exposed faces and filling the spaces.

4. The method of building roofs, which consists in securing a lower course of insulating board to a roof support and a spacing member substantially midway of the upper surface of the course, securing a second course of insulating board with its lower edge resting on the spacing member so as to be spaced above the surface of the first course, applying a hot coating of impervious material over the exposed faces and filling the spaces, and sprinkling crushed slate onto the hot coating.

15. 5. In a building roof, a plurality of sheets of insulation board arranged in partially overlapping relation to provide a roof covering of multiple thickness, the lower edge of each board being spaced from the upper face of the next lower board, and a continuous impervious coating extending over the upper faces of the projecting portions of the insulation boards and the lower ends thereof, and extending under said ends to enter into said spaces.

20. 6. In a building roof, a roof covering in the form of a multiple thickness of insulating board whose lower edges are opposite one another and spaced apart, and an impervious coating about the lower edges of each board and entering into the space between them to close the space and prevent the entry of water in between the superposed boards.

25. 7. In a building roof, a roof covering in the form of a multiple thickness of insulating board whose lower edges are opposite one another and spaced apart, an impervious coating about the lower edges of each board and entering into the space between them to close the space and prevent the entry of water in between the superposed boards, and a metal flashing strip about the coating which covers the lower edge of the lower board.

SALVATOR S. CALAFATI.
